SAMPLE CARD

Joseph Dember, Bronx, N. Y., assignor to Peerless Sample Card Co. Inc., New York, N. Y., a corporation of New York

Application March 2, 1935, Serial No. 8,984

2 Claims. (Cl. 206—82)

My invention relates to a new and improved sample card.

One of the objects of my invention is to make a sample card which can be manufactured at low cost and in large quantities.

Another object of my invention is to provide a sample card construction whereby the samples of cloth or the like can be mounted in a simple manner and at low cost, and to provide a device having minimum weight.

Other objects of my invention will be set forth in the following description and drawings which will illustrate two preferred embodiments thereof, it being understood that the above statements of the objects of my invention is intended to generally explain the same without limiting it in any manner.

Fig. 1 is a plan view of a sample card in the extended position.

Fig. 2 is a fragmentary perspective view of the sample card, in the partially folded position.

Fig. 3 is a sectional view on the line 3—3 of Fig. 1.

Fig. 4 is a sectional view on the line 4—4 of Fig. 1.

Fig. 5 is a perspective view showing one of the sample card elements, consisting of a piece of cloth or other material, having cardboard mounting devices at each end thereof.

Fig. 6 is a perspective view which illustrates a modification of Fig. 5.

Fig. 7 is a sectional view on the line 7—7 of Fig. 1.

Fig. 8 is a view similar to Fig. 1, and showing a modification of Fig. 1.

Fig. 9 is a fragmentary perspective view of the device shown in Fig. 8, in the partially folded position.

Fig. 10 is a sectional view on the line 10—10 of Fig. 8.

Fig. 11 is a perspective view, showing a modification of the sample card element.

Fig. 12 illustrates a modification of Fig. 11.

The device shown in Fig. 1 comprises four panels, A, B, C, and D.

This device can be made of cardboard or other flexible material and said panels are arranged to fold on the score lines 1, 2 and 3.

In order to make the device shown in Fig. 1, a blank is punched so as to form the slots S. These slots extend completely through the cardboard or other flexible material which is used for making the device.

In order to punch the slots S at minimum cost, the punching operation is performed while the

blank is in the folded condition so that the four panels or sections of said blank closely contact with each other.

Of course, the device can have any desired number of sections or panels.

It will be noted that there are a row of slots S adjacent each edge of the device, and that there are a row of said slots S at each side of each fold line 1, 2, and 3.

For convenience, it can be assumed that the 10 axis of the card is parallel to the long edge thereof, referring to Fig. 1.

It will be noted that each slot S has a length which exceeds the width thereof and that said slots S are parallel to said axis.

In order to reinforce the device at the fold lines 1, 2, and 3, a supplemental reinforcing strip 4 is connected by an adhesive or by other suitable means to the rear face of the device, at each fold line. These supplemental strips 4 also cover the 20 slots S which are adjacent said fold lines 1, 2, and 3.

When the device is held horizontally, and it is desired to fold the same, the panels A and B are bent upwardly along the line 1, the panel C 25 is bent downwardly along the line 2, and the panel D is bent upwardly along the line 3, so as to fold the device in the manner indicated in Fig. 2.

As shown in Fig. 2, the intermediate strip 4, 30 which is adjacent fold line 2, is located between the adjacent faces of panels B and C, when the device is folded.

Additional reinforcing and covering strips 5 are connected to the edges of the device by means 35 of an adhesive or the like in order to cover the edge slots S, at the rear surface of the device.

As shown in Fig. 3, the reinforcing strips 4 are glued or otherwise connected to the device only at the longitudinal edges of said strips 4, so that 40 substantial portions of the bodies of said strips 4 are not connected to the imperforate part of the rear wall of the device. The strips 4 and 5 may be made of paper or cloth.

Likewise, the strips 5 are connected to the rear 45 wall of the device only at the longitudinal edges of said strips. The reinforcing strips 4 and 5 therefore form flaps or pockets, which are unconnected to the imperforate rear wall of the device save at the edges of said strips. The edge strips 50 5 are equivalent to the inwardly turned edges shown in U. S. Patent No. 1,788,826.

The sample card element consists of a strip of cloth C' or other flexible material. A U-shaped mounting strip 6 is connected to each end of the 55

strip C', by means of any suitable adhesive. This strip 6 is made of cardboard or of any suitable material.

5 Each said strip 6 is provided with integral tabs 6a at its top and bottom. Said tabs are perpendicular to the sample strip C'.

Each said sample card element may have an identifying number N printed or otherwise indicated upon one of the mounting strips 6.

10 In order to mount the element C' upon the card, the tabs 6a are inserted into aligned slots S as indicated in Fig. 1. Each said tab 6a enters the pocket which is formed by the respective reinforcing strip.

15 In the embodiment shown in Fig. 6, I have shown a mounting strip 7 which is connected by adhesive or the like, only to one face of the strip C'. Said mounting strip 7 is provided with integral tabs 7a. This element is used in the manner previously indicated.

20 The embodiment illustrated in Fig. 8 is identical with the embodiment indicated in Fig. 1, save that the slots S are perpendicular to the longitudinal axis of the device instead of being 25 parallel to said longitudinal axis shown in Fig. 1.

Fig. 9 is identical with Fig. 2 save for the difference in the alignment of the slots S.

Fig. 11 shows a strip C' which is made of cloth or other suitable flexible material.

30 Mounting members 8, of U-shaped form, are connected to the edges of the strip C' by adhesive or any other suitable means. Said members 8 are provided with integral tabs 8a, and they stiffen the top and bottom edges of strip C'.

35 The embodiment shown in Fig. 12 is identical with that shown in Fig. 11, save that Fig. 12 shows a mounting tab 9 which is connected by adhesive or the like only to one side of the edge of strip C'. Said member 9 is provided with tabs 9a, which correspond to tabs 8a.

40 Referring to Fig. 1, it will be noted that the sample element C' cannot be pulled readily out of the device because the four tabs 6a enter respective slots S so as to resist an outward pull.

45 It will be noted that each strip which is used in the device shown in Fig. 8, is held in position by means of four tabs, and that continuous cardboard strips are connected to the top and bottom edges of C'.

50 However, the embodiment shown in Fig. 1 is superior to the embodiment shown in Fig. 8, for reliably holding the strips in position. If the element C' is pulled outwardly, the effect is to

cause the members 6 to move towards each other, which is resisted by the engagement of the tabs 6a with the walls of the slots S.

I have thus provided a simple and light-weight device, because it is unnecessary to connect each strip C' to a piece of cardboard having approximately the same dimensions as said strip. For example, in the embodiment of Fig. 11, the spaced members 8 are narrow and they are much lighter than a piece of cardboard of the same 10 size as the cloth sample.

When the device is folded, all the slots are located close to the superposed edges of the folded device, as generally indicated in Fig. 2. This makes it possible to punch the slots S at low 15 cost by using punching dies which operate adjacent said superposed edges, and before the reinforcing strips are applied.

The invention is particularly useful in connection with strips C' made of thin cotton material or the like, which is very flexible and which has substantially no inherent rigidity. However, the invention can be used with samples of woolen cloth and with samples of other materials of any weight.

20 I have shown a preferred embodiment of my invention, but it is clear that numerous changes and omissions can be made without departing from its spirit.

25 I claim:

1. In combination, a sample card having longitudinal rows of aligned openings, the openings in the respective rows being laterally aligned and a sample card element, said sample card element comprising a strip of flexible material having substantially no inherent rigidity, said strip having mounts connected to the ends thereof, said mounts being spaced from each other, said mounts having tabs which are adapted to enter four slots, said slots comprising laterally aligned pairs of slots, the slots of each pair being in different rows.

2. In combination, a sample card having rows of aligned openings, and a sample card element, said sample card element comprising a strip of flexible material having substantially no inherent rigidity, said strip having mounts connected to the ends thereof, said mounts being spaced from each other, said mounts having tabs which are adapted to enter four of said slots, said tabs being perpendicular to the longitudinal axis of said strip.

30 JOSEPH DOMBER.
